(57) **CLAIM**

The ornamental design for a six fold acupuncture mat, as shown and described.

DESCRIPTION

FIG. 1 is a front perspective view of a six fold acupuncture mat, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the six fold, acupuncture mat in an, unfolded position; and,

FIG. 10 is an enlarged view of a portion indicated in FIG. 1. The dash-dot-dash broken lines in the drawings indicate the boundaries of an enlarged view and form no part of the claimed design.
